UNITED STATES PATENT OFFICE.

WILLIAM H. NEEDHAM, OF WORCESTER, MASSACHUSETTS, ASSIGNOR TO BOSTON
PRESSED METAL CO., OF WORCESTER, MASSACHUSETTS, A CORPORATION OF
MAINE.

METHOD OF MAKING SKATE-KEYS.

1,261,153.

Specification of Letters Patent. Patented Apr. 2, 1918.

Application filed June 20, 1917. Serial No. 175,733.

To all whom it may concern:

Be it known that I, WILLIAM H. NEEDHAM, a citizen of the United States, residing at Worcester, in the county of Worcester 5 and State of Massachusetts, have invented a new and useful Method of Making Skate-Keys, of which the following is a specification.

This invention relates to a method of 10 making a skate key from a single piece of sheet metal.

The article itself is not claimed herein as it forms the subject matter of a divisional application Serial No. 186,783, filed by me 15 August 17, 1917.

It is the general object of my invention to improve the construction of articles of this type and to provide a cheaper and more effective method of manufacture therefor.

With this general object in view, my invention consists in certain constructions and methods of manufacture hereinafter described and more particularly pointed out 20 in the appended claims.

A preferred form of my invention is shown in the drawings in which—

Figures 1 and 2 are front and side elevations respectively of the key blank after the first operation has been performed;

Figs. 3 and 4 are a side elevation and end view of the key blank after the second operation has been performed;

Figs. 5 and 6 are a side elevation and end view after the third operation has been completed, and

Figs. 7, 8 and 9 are front and side elevations and end view of the completed skate key.

In manufacturing my improved key I 40 form the same from a single piece of sheet metal and entirely by pressing and punching operations. The first operation forms the blank shown in Figs. 1 and 2, said blank comprising a thumb-piece 10, a ribbed shank 45 portion 11 and an enlarged rounded end portion 12 disposed at a slight angle to the parts 10 and 11. The part 10 may be cut out as indicated at 13 and 14 so that it may conveniently serve as a wrench.

For the next operation the blank is placed upon a die in the position shown in dotted lines in Fig. 3 and a punch having a rounded end is brought down upon the blank, pressing it into the die and leaving it in the shape

shown in full lines in Figs. 3 and 4. The 55 blank portion 12 is formed into a cup 15 and the shank portion 11 and thumb-piece are bent upward nearly to the vertical position. The parts are left at a slight angle from the vertical, however, in order to provide 60 clearance for the punch in this and the succeeding operations. The object of forming the blank 12 at an angle to the shank 11 is to facilitate the forming of the cup 15 and the bending of the shank 11 to the position 65 shown in Fig. 3.

The third operation consists in punching a square hole 16 in the lower end of the cup 15, as shown in Fig. 6, the hole being of the same size as the skate shaft for which 70 the key is designed.

For the last operation the partially formed key is laid horizontally upon a special die block and a coöperating punch is brought down upon the key to produce the finished 75 article. In this operation the cup 15 is transformed into the four-sided tubular portion 17 fitting the skate shaft; and the shank portion 11 is offset to bring the thumb-piece 10 substantially into alinement with the axis 80 of the key. This fourth operation completes the formation of the key.

I am thus enabled to form a skate key of unusual strength and utility from a single 85 piece of sheet metal by a series of four simple operations. These operations may all be performed with great rapidity and the skate key shown in Figs. 7 to 9 can thus be manufactured at an extremely low cost.

While I have indicated herein the preferred steps in the formation of my improved skate key, certain novel features of the article itself are not necessarily limited to the particular steps by which it is formed, as it will be evident to those skilled in the art that a similar article may be produced by a different series of steps, and therefore I do not wish to be limited to the details of operation or construction herein disclosed otherwise than as set forth in the 90 claims.

What I do claim is:—

1. The process of making a sheet metal skate key which consists in making a blank, forming a cup at one end of said blank, perforating the bottom of said cup to fit the 105 skate shaft, and finally shaping the sides of said cup to fit said shaft.

2. The process of making a sheet metal
skate key which consists in making a blank
with a shank portion and having one end
portion at a slight angle to said shank portion
5, forming a cup from said end portion,
perforating the bottom of said cup to fit the
skate shaft, and thereafter pressing the sides
of said cup into tubular form with an opening
therethrough also fitting said shaft.
- 10 3. The process of making a sheet metal
skate key which consists in making a blank,
comprising a thumb-piece, a ribbed shank
portion, and an end portion joining said
shank portion at a slight angle, bending
said end portion to form an approximate 15
right angle with said shank portion and
simultaneously forming a cup from said end
portion, perforating said cup, compressing
the walls of said cup to form a flat-sided
20 tubular portion having an opening of the
same size as said perforation, and simul-
taneously offsetting said shank portion to
bring the thumb-piece into axial position.

In testimony whereof I have hereunto
affixed my signature,

WILLIAM H. NEEDHAM.
